UNITED STATES PATENT OFFICE.

WILLIAM H. LANG, OF CHICAGO, ILLINOIS, ASSIGNOR OF ONE-HALF TO GEORGE W. PHILLIPS, OF CHICAGO, ILLINOIS.

AUTOMATIC SKIP-BUCKET LOADING DEVICE.

Application filed March 12, 1923. Serial No. 624,442.

To all whom it may concern:

Be it known that I, WILLIAM H. LANG, a citizen of the United States, and a resident of the city of Chicago, county of Cook, and 5 State of Illinois, have invented certain new and useful Improvements in Automatic Skip-Bucket Loading Devices, of which the following is a specification.

My invention relates to improvements in 10 automatic skip bucket loading devices, and has for its principal object the provision of an improved construction of this character which will be highly efficient in use and economically in manufacture.

15 I aim among other things to provide certain combinations of elements and parts operable by a skip bucket of the ordinary construction for automatically filling the bucket and for automatically interrupting 20 the supply of material discharged into the bucket, the device being especially designed for use in connection with a skip bucket adapted to be manipulated in a vertical 25 plane between skip guides of the ordinary construction.

Other objects will appear hereinafter.

The invention consists in the combinations and arrangements of parts hereinafter described and claimed.

30 The invention will be best understood by reference to the accompanying drawings forming a part of this specification, and in which,

Fig. 1, is a side elevational view of the 35 loader embodying the invention;

Fig. 2, is a front elevational view of the same;

Fig. 3, is a sectional view taken substantially on line 3—3 of Fig. 2, and

40 Fig. 4, is a sectional view taken substantially on line 4—4 of Fig. 2.

In carrying the objects of the invention into effect and with reference to the accompanying drawings I associate my automatic 45 skip bucket loader with a hopper 10 of suitable shape and construction designed especially to receive the material to be loaded into the skip bucket. The hopper 10 is provided with a discharge opening 11 and a chute 12 having its end 13 inserted in the opening 11 and fixed thereto by any suitable means. The hopper 10 is preferably of the type having its interior conical in shape terminating around the opening 11 so that 50 by the laws of gravity the material in the

hopper will work toward the opening 11, this construction avoids the necessity of pushing the material to and through the discharge opening. In Fig. 3 I prefer for reasons to be hereinafter understood to 60 bevel the edges indicated at 14 of the vertical side walls 15 of the chute 12. The chute 12, as shown, is of the open top type, however a closed top type chute or any other chute of the ordinary construction 65 will serve the purposes as well.

In Fig. 1, 16 indicates a skip bucket mounted to be vertically manipulated between the skip guides of a shaft, not shown, by the usual means and of the ordinary construction. On opposite sides of the bucket 16 and in spaced relation with respect to the adjacent sides of the bucket are vertically extending guides 17 and 18 providing channels 19, the guides being provided with 70 attachment means indicated at 20 and bracing means indicated at 21. The position or location of the guides with respect to the bucket is such that a portion of the bucket indicated at 22 will project beyond the outer 75 corresponding faces of the guides as best shown in Fig. 1. A yoke 23 including a transversely positioned rod member 23 having its opposite ends 24 extending into the channels is adapted to reciprocate vertically 80 with respect to the guides in a manner to be more fully hereinafter understood. Connected to the member 23 are spaced links 24 and 25 having integral stops 25' formed at one end thereof and pivotally connected 85 at the other ends to a rod member 26 pivotally connected to an auxiliary chute 26 as at 27, Fig. 3. The auxiliary chute 26 is pivotally connected to the chute 12 as at 28. The chute 26 is designed especially to interrupt the passage of material through the chute 12 to the bucket 16 and for this purpose it is provided with an extension or 90 apron 29 having its wall 30 arcuate in shape and corresponding to the contour of 100 the bevelled edges 14 of the vertical walls of the chute 12. The chute 26 is further provided with side walls 31 and top and bottom walls 32 and 33 respectively and with a discharge opening 34. The wall 32 extends to a point rearwardly from the discharge opening to provide a stop edge 35 which is adapted to rest upon the top edges 105 of the vertical walls of the main chute when the auxiliary chute is in the position illus- 110

trated in dotted lines in Fig. 1. When the chute 26 is in the position shown by dotted lines in Fig. 1 the chute is retained in this position by means of weights 36 preferably carried by the walls 31.

It will be readily seen by inspection of Fig. 1 that when the chute 26 is in the position shown by dotted lines the wall 30 of the apron interrupts the passage through the chute 12 and when the chute 26 is in the position best illustrated in Fig. 3 the passage through the chute 12 is unobstructed and the material from the hopper 10 is free to pass into the skip bucket 16.

15 The operation of my automatic skip bucket loading device is as follows: The bucket 16 upon being moved downwardly between the usual skip guides comes into contact with the member 23 of the yoke 23', the member 23 upon first coming into contact with the bucket is in the position shown in dotted lines in Fig. 1 and the chute 26 is in the position shown in dotted lines in that figure. Due to the down-force of 25 the bucket on the yoke 23' the auxiliary chute is caused to pivot into operative position and the wall 30 of the apron 29 moves with the auxiliary chute from obstructing the passage of material passing 30 from the hopper to the bucket. As long as the bucket remains in the position illustrated in Fig. 1 in full lines the chute 26 will be held in operative position thereby, but upon vertical movement of the bucket 35 the top of the bucket comes into contact with the walls of the auxiliary chute and as the bucket moves upwardly the chute also will pivot upwardly. The bucket continues to force the chute 26 to pivot upwardly until a point is reached where further pivotal movement, is brought about by 40 the weights 36.

It will be seen that no manual labor is necessary to operate the chute 26 to bring 45 it into operative position and to move it again to its inoperative position as this operation is accomplished solely by the skip bucket.

While I have illustrated and described 50 the preferred form of construction for carrying my invention into effect, this is capable of variation and modification without departing from the spirit of the invention. I, therefore, do not wish to be limited to the 55 precise details of construction set forth, but desire to avail myself of such variations and modifications as come within the scope of the appended claims.

Having described my invention, what I 60 claim as new and desire to secure by Letters Patent is:

1. An automatic loading device for a skip

bucket traveling between vertical guide rails, said device comprising a fixed chute, a chute pivoted to said fixed chute and having an extension with a curved wall to close the passage provided by said chutes, a yoke swingably mounted on said pivoted chute, for operating said chute, and a transverse rod in said yoke and having its ends traveling in said guide rails, said rod being engaged by the bottom of said bucket traveling in said guide rails for swinging said pivoted chute with its closing means to provide a continuous passage through said chutes.

2. An automatic loading device for a skip bucket traveling in vertical guide rails, said device comprising a fixed chute, a chute pivoted to said fixed chute and having an extension with a curved wall for closing the passage through said fixed chute, a front and top wall on said pivoted chute arranged for preventing material from overflowing said bucket when said chute is lowered and also adapted to engage said fixed chute for holding said pivoted chute when in its raised position, and a yoke with a transverse rod swingably mounted on said pivoted chute, said rod traveling in said guide rails and being engaged by said bucket for swinging said pivoted chute with its curved wall to open the passage through said chutes.

3. An automatic loading device for a skip bucket traveling in vertical guide rails, said device comprising a fixed chute, a chute pivoted to the bottom of said fixed chute and having an extension with a curved wall for closing the passage through said fixed chute, a front and a top wall on said pivoted chute arranged for preventing material from overflowing said bucket when said chute is lowered and also adapted to engage said fixed chute for holding said pivoted chute when in its raised position, a weight secured to each side wall of said pivoted chute and positioned at the upper corners thereof, and a yoke including side bars pivotally mounted with an upper transverse rod beneath said pivoted chute and having a lower transverse rod with outwardly extending ends traveling in said guide rails and being engaged by said bucket for swinging said pivoted chute with its curved wall to open the passage through both of 115 said chutes.

In testimony whereof I have signed my name to this specification in the presence of two subscribing witnesses.

WILLIAM H. LANG
